UNITED STATES PATENT OFFICE.

CHARLES W. HARROLD, OF CLEVELAND, OHIO, ASSIGNOR TO THE HARRIS AUTOMATIC PRESS COMPANY, OF CLEVELAND, OHIO, A CORPORATION OF OHIO.

SHEET DETECTOR.

Application filed December 20, 1921. Serial No. 523,760.

My invention relates to automatic sheet-detectors used more particularly for sheet-fed printing machines whereby one of the cylinders may be tripped not only upon the failure of a sheet being advanced to the front stops, but also for preventing an improperly registered sheet from passing into the printing-machine. My improved sheet-detector also has for its object the tripping of the press in case one corner of the sheet is mutilated or folded back upon itself so that the sheet fails to present an even edge along the front or leading edge of sheet. A further object is to provide a sheet-detector of such construction in its component parts as to be extremely sensitive in operation with capabilities of adjustment so as to accommodate the detector mechanism for different kinds of stock that is fed up to the front stops preparatory to being seized by the grippers on the impression-cylinder.

Other objects and advantages of my invention will be apparent from the following detailed description thereof, and a preferred embodiment is illustrated in the accompanying drawings in which—

Fig. 1 is a diagrammatic sectional side elevation of a portion of a printing-machine and sheet-feeding mechanism equipped with my sheet-detector, the parts being shown when no sheet is being advanced to the press;

Fig. 2 is a view similar to Fig. 1 showing the parts after a sheet has been properly registered and presented for printing.

Fig. 3 is a similar view showing the position of some of the operating parts should a sheet be improperly presented;

Fig. 4 is a fragmentary sectional plan view the section being taken on the line 4—4 shown in Fig. 1;

Fig. 5 is a diagrammatic sectional side view taken on the line 5—5 of Fig. 4 looking in the direction of the arrow and showing means to throw off the impression-cylinder.

Fig. 6 is a detail side view of the detector finger and front stop.

Similar numerals refer to similar parts throughout the several figures.

Referring to the drawings, the frame 8 supports the bearings for the impression-cylinder 9 mounted on the shaft 10 which is carried at both ends in eccentric bushings 11 (only one being shown in Fig. 5) to move the impression-cylinder 9 into and out of printing relation with its coacting printing member by shifting the bushings 11. Since this is a common form of printing-press construction and is well-known in the art, it is not shown in detail in the drawings, and the operation of the tripping of this cylinder 9 will be hereinafter more specifically set forth.

The frame 8 also has journalled therein the upper feed-roll shaft 12 carrying a series of upper feed-rolls 13, and the lower feed-roll shaft 14 carrying a series of lower feed-rolls 15. Only one set of such feed-rolls is shown in Figs. 1, 2 and 7, while three sets are illustrated in Fig. 4, and these feed-rolls are rotated in unison by any suitable means not necessary to be shown. The lower feed-rolls 15 project through suitably formed slots 16 in the register plate 17 to which the successive sheets are advanced by the usual carrier 70 tapes 18 passing around pulleys 19 as shown in Fig. 2.

Projecting through the slots 16 are a series of front stops 20 against which the leading edge of the sheet is alined before being advanced by the feed-rolls 13 and 15 to the usual grippers on the cylinder 9. Each of these stops 20 is adjustably mounted on the transverse shaft 21 by set-screws 22, and the shaft 21 is oscillated to raise and lower the stops 20 in suitably timed relation with the actuation of the feed-rolls by the reciprocating rod 23 pivoted to the arm 24 secured to one end of the shaft 21 as shown in Fig. 4.

Adjacent the front stops 20 are a series of detector fingers 25 preferably one detector finger for each stop. These fingers 25 likewise project through the slots 16, and normally occupy a position on a line parallel 95 with the front stops 20 and slightly in advance of the stops as shown in Figs. 1 and 4. In Figs. 1, 2 and 3 only one set of fingers

and stops are shown with their actuating devices, the other sets along with their separate actuating devices being duplicates are therefore not further shown or described. 5 Each finger 25 is adjustably clamped to the upper end 26 of the rocking member 27 pivoted on the pin 28 secured to the bracket 29 affixed to the front stop 20. The end 26 has the curved slot 30 formed therein 10 through which the thumbscrew 31 projects to variably change the relative positions of the finger 25 on the lever end 26, and thereafter clamp same to secure the requisite setting of the finger 25 with the stop 20, according to the different grades or stock that is being fed to the press. The coil spring 32 between the top of the end 26 and the front stop 20 normally holds the finger 25 in a vertical position in advance of the stop as shown in Fig. 1. The lower end of the rocking member 27 carries the pin 33 which engages and slides in the vertical slot 34 formed in the upper end of the reciprocatable rock-lever 35 pivoted on the pin 36 projecting through the longitudinal slot 37 cut in the lever 35, the pin 36 being secured to the bracket 38 adjustably secured to the tie-rod 39 by the screw 40. The lower end of the lever 35 carries the interposing thrust block 41 projecting laterally from such lever 35 as shown. The bracket 38 has the inclined arm 42 formed integrally therewith in which are journalled the transverse shafts 43 and 44. The shaft 44 carries the double arm lever 45 which is rocked back and forth in each cycle of operation by the reciprocating rod 46 pivoted to the lower arm 47 of this lever 45. The shaft 43 carries the collar 48 affixed by a set-screw (not shown) 30 to the shaft 43 from which the arm 49 projects over the lever 45 as shown in Fig. 1. The lever 45 has the jaw 50 formed in its end while the arm 49 has the jaw 51 in its outer end, the two jaws providing a dovetail opening between them and they are arranged to coact with the thrust block 41 projecting from the end of the lever 35. This mechanism, as hereinbefore explained, is duplicated for each of the detector fingers 25. To the shaft 43 is also secured the integral arm or projection 52 adapted to engage the end of the latch 53 pivoted on the pin 36, the latch being normally held in the notch 54 of the collar 55 on the shaft 56 by the coil spring 57.

The shaft 56 is the throw-off shaft for the tripping of the impression-cylinder 9, and is held under tension by the torsion spring 60 shown in Fig. 4 so that when the latch 53 is lifted out of the notch 54 the shaft 56 is turned in a clockwise direction by the spring 60 to rock the arm 61 which is connected by the rod 62 to the arm 63 secured to the eccentric bushing 11 to trip the cylinder 9 as shown in Figs. 4 and 5. The hand-lever

64 is secured to the shaft 56 to throw on the impression, and compress the spring 60 while allowing the latch 53 to be reset in engagement with the notch 54 when the lever 45 and arm 49 are in the positions shown in Fig. 1.

The operation of my improved sheet-detector is substantially as follows: The detector fingers 25 are normally occupying a position slightly in advance of the row of front stops 20 as shown in Figs. 1 and 4, and are preferably located near each front corner to be engaged by the leading edge of the sheet. As the sheet 65 (Fig. 2) is fed up to the stops 20 the detector fingers 25 are forced back or depressed by the sheets until flush with stops 20, which movement carries the thrust block 41 out of its normal position between the jaws 50 and 51 as shown in Fig. 1, and swings the block 41 clear of the coacting lever 45 and arm 49 through the oscillation of the rock-lever 35 on the pin 36 by the rocking of the member 27 on the pin 28, the lever 45 approaching the arm 49 as shown by the arrows in Fig. 2. After the sheet 65 is side-registered by devices not necessary to be shown, the stops 20 are lowered to the level of the plate 17 and the sheet is fed on to the cylinder by the joint action of the two feed-rolls 13 and 15 rotating in the direction of the arrows shown in Fig. 2. The sheet 65 further depresses the fingers 25 to the position shown in Fig. 2 as the sheet is being advanced to the cylinder 9. In this construction, the detector fingers 25 are forced backward by the leading edge of the sheet 65 until it contacts with the front stops 20 and the fingers remain in this position until the front stops are lowered by the oscillation of the shaft 21 which lowers the arms 29 on which the fingers 25 are pivoted; then the advancing edge of the sheet 65 passes over the tips of the fingers 25 as they are swung clear of the path of the sheet. Hence the movement of the detector fingers 25 is first a tilting of the fingers by the advancing sheet followed by a simultaneous movement of both fingers and stops out of the path of the sheet caused by a lowering of the arms 29.

However if a sheet is not presented to the front stops 20 at the proper time, or if one corner of the sheet lags behind, or if a corner of the sheet is torn or folded back upon itself so that any one of the fingers 25 is permitted to remain in its upright position whereby the thrust block 41 is retained in its position in the opening between the jaws 50 and 51 as the lever 45 is raised in its normal reciprocation in each cycle, the upward advance of the lever 45 will lift the arm 49 through the block 41 being caught between the jaws 50 and 51 and thereby the latch 53 is lifted from the notch 54 as shown in Fig. 3. The latch

being released the rod 62 is immediately moved to the left by the torsion spring 60 to throw the impression-cylinder 9 out of printing relation. The latch 53 is restored to engagement with the notch 54 by the lever 64 being operated to turn the collar 55 in an anti-clockwise direction after the lever 45 has been lowered to the position shown in Fig. 1, the spring 57 lowering the arm 49 as the latch 53 is reset in this notch 54. The shape and proportions of the thrust block 41 are such as to readily permit the entrance of this block between the dovetail opening formed between the jaws 50 and 51 to secure a fine adjustment and setting for the action of the throw-off devices.

My improved sheet-detector may be utilized to perform a double function in that it will trip the impression-cylinder if no sheet is fed to the front stops, and it will also trip the press when a sheet is fed but fails to reach an accurate front register position for any reason; it will also trip in case a corner of the sheet is torn or folded back or fails to present an even edge along the front stops after the front and side registering operations have been completed, whereby any one of the suitably arranged detector fingers is left in its upright position at that particular movement in the cycle of operation when a properly registered sheet should remove all the detector fingers from their normal position in advance of the front stops.

Various changes may be made in the constructions shown without departing from the principles and scope of the claimed invention which is not to be confined to the particular constructions herein described and illustrated in the accompanying drawings, which show and describe an embodiment of my invention used to throw-off the impression-cylinder; however my improvements may be likewise used with the intermediate or transfer-cylinder of an offset press to simultaneously separate same from the plate and impression cylinders.

I claim as my invention:

1. In a sheet-detector, a plurality of oscillatable detector fingers stationarily positioned in the path of the sheet, but movable by the advancing sheet, a throw-off mechanism, and connections comprising a pair of coacting jaws and interposed thrust block between each of said fingers and throw-off mechanism to operate the latter whenever any of said fingers is not swung forwardly by the edge of the sheet from its normal position and said block is retained between said jaws.

2. In a sheet-detector, front stops, a plurality of oscillatable detector fingers stationarily positioned in the path of the sheet, but each movable by the advancing sheet when alined against all said stops, a throw-

off mechanism, and connections comprising a pair of coacting jaws and interposed thrust block between each of said fingers and throw-off mechanism to operate the latter whenever any of said fingers is not swung forwardly by the leading edge of the sheet from its normal position and said block is retained between said jaws.

3. In a sheet-detector, a plurality of detector fingers normally positioned in the path of the sheets but movable forwardly by the advancing sheet, a throw-off mechanism, and mechanically operated connections comprising a pair of movable jaws and an interposed thrust block between each of said fingers and throw-off mechanism to operate the latter when any of said fingers is not moved from its normal position and said block is maintained in its operative position between said jaws.

4. In a sheet-detector, front stops, means for advancing a sheet to said stops, a plurality of oscillatable detector fingers stationarily positioned in advance of said stops in the path of the sheet, but movable when engaged by the leading edge of the sheet, a throw-off mechanism, and connections comprising a pair of coacting jaws and interposed thrust block between each of said fingers and throw-off mechanism to operate the latter whenever any of said fingers is not swung forwardly by the edge of the sheet from its normal position and said block is retained between said jaws.

5. In a sheet-detector, front stops, a plurality of detector fingers normally positioned in advance of said stops but movable forwardly and downwardly from the path of the sheet when engaged thereby, a throw-off mechanism, and mechanically operated connections comprising a pair of movable jaws and an interposed thrust block between each of said fingers and throw-off mechanism to operate the latter whenever any of said fingers is not moved from its normal position and said block is maintained in its operative position between said jaws.

6. In a sheet-detector, front stops, a series of movable fingers adapted to be alined with said stops, a throw-off mechanism, and connections comprising a pair of coacting jaws and interposed thrust block between each of said fingers and throw-off mechanism to operate the latter when any of said fingers is not in alinement with said stops and said block is retained between said jaws.

7. In a sheet-detector, front stops, a movable finger adapted to be alined with said stops, a throw-off mechanism, and connections comprising a pair of coacting jaws and interposed thrust block between said finger and throw-off mechanism to operate the latter when said finger is not brought in alinement with said stops and the sheet and said block is retained between said jaws.

- 4-
8. In a sheet-detector, spaced-apart front stops located in the path of the sheet, a plurality of independently movable fingers each adapted to be alined with said stops by the leading edge of the sheet, a throw-off mechanism, and connections comprising a pair of coacting jaws and interposed thrust
  - 5

block between each of said fingers and throw-off mechanism to operate the latter whenever any of said fingers is not brought 10 in alinement with said stops and said block is retained between said jaws.

CHARLES W. HARROLD.
